CONTAINER CLOSURE

Walter F. Straub, Chicago, Ill., assignor to W. F. Straub & Company, Chicago, Ill., a corporation of Illinois

Application June 4, 1938, Serial No. 211,856

13 Claims. (Cl. 215—44)

This invention relates to improvements in container closures and more particularly concerns closures which are adapted to control a flow of material therethrough from dispensing containers.

One object of the invention is to provide an improved container closure of this type which is simple in construction and highly efficient in use and which can be produced at low cost by simple manufacturing methods from inexpensive and readily available materials.

In container closures of the type with which this invention is primarily concerned, the crown of the closure has a discharge area including a port through which material from within the container can be poured when the container is tilted. To close the port, a slidable cover is mounted upon the closure to be shifted manually into port-closing or opening positions. Some prior closures of this type, in addition to having means for retaining and guiding the slidable cover, require special stops on the closure or the cover for limiting the extent of opening or closing movement of the cover. In other prior forms of closure, the ends of the cover have been engageable with the walls of the container or with marginal beads or flanges such as are found on dredge-top cans.

Such prior expedients have generally been restricted to use with containers for granular or powdered materials, spices and the like. Many have been impractical because of the high cost of manufacture or the difficulty of effectively manipulating the same, or for other structural deficiencies. Few, if any, have provided an inexpensive construction adaptable for use with dispensing containers for viscous or syrupy materials such as honey.

It is therefore an object to provide a cover of inexpensive construction adaptable for use on containers for viscous substances such as honey.

More specifically, it is an object to provide a container closure which can be used effectively on dispensing containers for syrupy materials and which has an easily manipulable, slidable cover for the discharge opening therein, the cover being guided for opening and closing movements by means engageable with the handle of the cover to limit the movement of the cover to its extreme open and closed positions.

Another object resides in the provision of an improved liner construction for a container closure of this character.

A further object is to provide a container clo-

sure in which a partially severed portion of the closure within an area protected by the sliding cover is adapted to be bent away to form a discharge opening.

A still further object is to provide a container closure which is apertured or partially severed for the purpose of providing a discharge opening but is sealed against the escape of material therethrough before the closure is to be opened.

Still another object is to provide an improved dispensing closure cap and slidable cover therefor, and a method of assembling the same.

Other objects and advantages will become apparent in the following description and from the accompanying drawings in which:

Figs. 1, 2 and 3 are perspective views of a container closure embodying this invention, applied to a bottle tilted for pouring and showing the slidable cover of the closure in various positions.

Fig. 4 is a rear plan view of the closure.

Figs. 5 and 6 are sectional elevational views taken substantially along lines 5—5 and 6—6 of Fig. 4.

Fig. 7 is an enlarged fragmentary transverse sectional view taken substantially along line 7—7 of Fig. 3.

Fig. 8 is a rear plan view of a modified form of the invention.

Fig. 9 is a transverse sectional view of a further modified form of the invention.

Fig. 10 is a perspective view showing the closure in the course of assembly.

Fig. 11 is a transverse sectional elevational view of another form of the invention.

Fig. 12 is a top plan view of the device shown in Fig. 11 with certain parts broken away.

Fig. 13 is a transverse sectional view similar to Fig. 11 but showing certain parts in different operative relationships.

Fig. 14 is a sectional plan view taken substantially along line 14—14 of Fig. 13.

While the invention is susceptible of various modifications and alternative constructions, I have shown in the drawings and will herein describe in detail, the preferred embodiments, but it is to be understood that I do not thereby intend to limit the invention to the specific forms disclosed, but intend to cover all modifications and alternative constructions falling within the spirit and scope of the invention as expressed in the appended claims.

On one preferred embodiment of the invention, the closure is constructed as an annular cap adapted to be attached to a dispensing container such as a bottle 16 of any desired shape

which has a generally cylindrical pouring neck 17 to receive the cap. The closure cap 15 may be stamped or spun from sheet metal and may have a generally flat end wall or crown 18 merging with an integral, peripheral attachment flange 18^a. The attachment flange 18^a may be provided with spaced, inwardly projecting lugs 19 of conventional form for removable engagement with well-known lock-type threads 20 upon the bottle neck 17 (Figs. 5 and 9). If it is desired to connect the cap 15 permanently to the bottle neck 17, the edge of the flange 18^a may be spun after assembly with the container to provide an inturned flange 21 to engage within a shoul- 15 dered groove 22 in the bottle neck (Figs. 11 to 14).

In order to avoid the necessity of removing the cap 15 from the bottle neck 17 when it is desired to pour material from the bottle, and also to maintain the discharging stream of material 20 under control, the cap is provided with an opening 23 closed by a slideable gate or cover 24. The opening 23 is located near the margin of the crown 18 adjacent to the attachment flange 18^a and provides only a limited discharge area. Preferably, the outer or pouring edge of the opening 23 is formed on a radius conforming to the annular outline of the cap and may be spaced from the attachment flange 18^a by an intervening threshold strip 25. This strip 25 is narrow enough 25 to permit unobstructed flow of material from the bottle neck 17 and preferably is slightly narrower than the thickness of the bottle neck wall. This will expose a portion of the end edge 30 of the bottle neck. The arcuate shape of the pouring edge of the aperture and the relationship of the strip 25 to the end edge of the bottle neck will facilitate pouring fluid from the container in a smooth, formed stream.

Furthermore, the strip 25 serves to coat with 40 the remaining marginal portions of the crown to bear against a sealing gasket or liner 27 which lies against and spaces the inner face of the crown from the end edge of the bottle neck. Such liner may be weakened on a coaxial annular line 45 as by means of scoring or perforations indicated at 28 (Fig. 8). The radius of the weakened line 28 is preferably coincident with the radius of the arcuate pouring edge of the discharge opening 23 in the cap and will thus always register with the latter when assembled with the cap. Through 50 this arrangement, when it is desired to open the bottle for pouring, the slideable cover is opened to expose the discharge opening 23 and the underlying portion of the liner 27 is severed along the weakened line 28 by pushing such portion out of the plane of the liner toward the interior of the bottle as shown in broken outline in Fig. 6 and in full outline in Fig. 7.

The slideable cover 24 is preferably of a length 60 substantially equivalent to the diameter of the closure cap 15 so that it will extend entirely across the center of the cap into closing relation with the discharge opening 23. In order to avoid unnecessary projections, the ends of the cover 24 are preferably shaped to conform to the peripheral outline of the crown of the cap in the closed position of the cover. Moreover, the forward end of the cover is preferably formed with a relatively abrupt edge so that as the cover is slid 70 toward closing position during a pouring operation, the stream of discharging material will be gradually but definitely cut off. This is of particular advantage where the discharging material, indicated at 29 in Fig. 2, is a viscous or syrupy 75 fluid such as honey.

Thus, referring to Figs. 2 and 7, the cover 24 in moving to a closed position first causes an attenuation of the fluid at the exposed portion of the end edge of the bottle and then completely closes the opening 23 by coacting with the threshold strip 25. The spacing between the cover 24 and the end edge of the bottle is so slight that after the forward edge of the cover reaches a position opposite said edge (full line position Fig. 7) the flow of the viscous material will be substantially stopped before the cover is completely closed. Continued closing movement of the cover will attenuate such fluid as is left and will finally cut it off when the opening 23 is fully closed (broken line position Fig. 7). As a result of this arrangement, substantially all of the viscous material that discharges from the bottle will pass away from the cap 15 by the time the cover 24 is fully closed and thus avoid outside accumulation of material on the cap at the forward end of the cover when the bottle is returned to non-pouring position. If any of the material tends to adhere to the threshold strip 25 after the flow of discharging material has been stopped, the final movement of the cover 24 thereacross to 25 fully closed position will substantially clean the material away.

In order to facilitate manipulation of the slideable cover 24, it is provided with an intermediate handle or finger piece 30. In the present instance the cover is made of an originally flat plate or strip of sheet metal and the finger piece 30 is formed by folding the central transverse portion of the strip upon itself and bending the folded portion to a position at a right angle to the strip proper. Thus, the slide cover with its finger piece has an inexpensive but satisfactory construction.

As shown in Figs. 1, 2 and 3, the slide cover can be easily manipulated through the medium 40 of the finger piece 30 by one finger of the hand in which the associated container 16 is held. Thus, the container may be tilted and held over the place where the material is to be poured (Fig. 1) but the material will be held in by the 45 closed cover 24. Then the finger piece 30 may be engaged by an upward sweep of the index finger to slide the cover open and hold it there (Fig. 2). After the desired quantity of material has 50 discharged, the index finger may be shifted to 55 the opposite side of the finger piece to slide the cover closed (Fig. 3). This arrangement has the further advantage of enabling control of the volume of the stream 29 of flowing material simply by adjusting the position of the cover 24 to regulate the amount of opening.

Means for retaining and guiding the cover 24 in its opening and closing movements upon the cap 15, in the present instance comprises a plurality of offset lugs or tongues 31 which are 60 struck out of the crown 18. These tongues 31 preferably comprise two spaced pairs which are in opposed alignment to engage respectively the front and rear sections of the cover slide 24 on opposite sides of the finger piece 30. The liner 27 will prevent escape of material through the openings which are left in the crown of the cap by the striking out of the tongues 31.

An additional function of the retaining and guiding tongues 31 herein is to serve as positive 70 limiting stops to determine the fully open and fully closed positions of the cover slide 24. To this end, the pair of tongues 31 which engages the front section of the cover is so located as to engage the base of the finger piece 30 and stop 75

the cover in the fully closed position (Figs. 1, 4 and 6). On the other hand, the rear pair of tongues 31 is so located as to permit the cover to be moved to fully open position. There the 5 finger piece 30 will be engaged by the rear tongues to stop further opening movement of the cover (Figs. 2 and 6). The spacing between the pairs of tongues 31 is less than the lengths of the front and rear sections of the cover 24 so that in its 10 movement the cover cannot slide out from under the tongues 31.

Assembly of the slide cover 24 with the cap may be effected simply and quickly without disturbing the guiding and retaining tongues 31. 15 All of the tongues can therefore be fully formed prior to the assembly operation. To this end the handle 30 is initially formed as an open fold of substantial V-shape so that, when one of the 20 sections of the cover 24 is inserted between one pair of the tongues 31, the other pair of tongues 31 can be received within the mouth of the V in readiness to receive the remaining section of the cover therebetween (full line position Fig. 10). After the cover has been thus positioned, the 25 handle fold is pinched closed (dot and dash position Fig. 10). This can be effected either before or after the cap and cover are relatively shifted to move the pair of tongues 31 out of the V through a pair of appropriately dimensioned 30 slots 31^a opening inwardly from the opposite edges of that side of the handle which joins said remaining section of the cover. The slide cover will thereafter be retained permanently by the tongues 31.

35 Advantage can be taken of the springiness inherent in the metal or other suitable material of which the cover 24 is made to assist in holding the cover in any position to which it is moved between the pairs of tongues 31. Herein the 40 opposite sections of the cover are so related that after the handle fold has been pinched closed, the sections will be in slightly divergent planes. As a result, the clearance between the offset portions of the tongues 31 and the crown 18 of the 45 cap will be taken up by the sections of the slide cover which will engage the tongues and the crown with a slight frictional resistance. Herein this effect is attained by having the opposite sections of the cover initially in substantially a 50 common plane so that when the handle fold is pinched together the sections will be drawn up into diverging relationship. This also results in forcing the extremities of the sections against the crown 18 and aids in attaining the attenuating effect upon the discharging viscous stream 55 29 hereinbefore described.

The crown of the cap may be made air-tight by coating the inner surface thereof with a sealing material such as wax, indicated at 32 in Fig. 4. Thus, slight cracks around the tongues 31 and between the cover 24 and crown will be closed. Moreover, the wax will tend to hold the cover 24 in its closed position until it is desired to open the container and the seal is broken by 60 sliding the cover open.

65 It may be desired to seal the closure with a liner that will not require to be punched out for dispensing purposes. For this purpose a modified form of liner 35 (see Fig. 9) which is imperforate may be provided to seat sealingly upon the edge of the bottle neck 17 prior to opening the bottle for dispensing therefrom. This liner 35 can be removed by unscrewing the cap before dispensing from the container. Thereafter an auxiliary ring gasket 36 which is frictionally held

within the cap 15 will provide a seal between the crown 18 of the cap and the edge of the bottle neck 17.

In another form of the invention (see Figs. 11 to 14), the cap 15, instead of having a punched out discharge opening, may be provided with a tongue 37 scored or severed from the crown on three sides and bendable out of the plane of the crown when it is desired to open the cap for dispensing. In this form of the invention, a liner 38 within the cap may be weakened along an annular line 38^a coincident with the severance which defines the end of the tongue 37. Then when the tongue 37 is pushed inwardly to form a discharge opening, the liner will be separated thereby along the coincident portion of the line 38^a and bent inwardly to form a tongue 39 (Figs. 13 and 14).

In order to avoid leakage through the line of separation in the crown of the cap at the tongue 37 during shipment or storage, a breakable seal is preferably provided therefor. Herein such a seal may be effected by a solidifiable material such as suitable lacquer, gum, wax or the like applied over and around the line of severance, 25 as indicated at 40 in Fig. 12. Such sealing means 40, since it is interposed between the crown of the cap and the cover slide 24, may serve also to seal the cover slide in closed position until the cover is forcibly opened to break the seal. 30 Thus, the cover will be held positively in protective relation to the bendable tongue 37 until the container is to be opened.

From the foregoing it will be apparent that the 35 invention attains a number of important advantages among which may be mentioned the simplicity and ease with which the closure cap and slideable cover may be manufactured and assembled and the efficient manner in which the cover controls the flow of material through the cap. 40 Important features in attaining a low cost of production are the novel method of assembling the cap and slideable cover and the unique construction whereby the same means that retains and guides the slideable cover also coacts with the 45 finger piece of the cover to define the open and closed limits of the range of movement of the cover. Another important feature resides in the cooperation of the slide cover 24 with the exposed edge of the bottle neck to cause an attenuation 50 of the stream of liquid before finally closing the pouring opening. Moreover, although the crown of the closure is apertured, it can be effectively sealed to prevent accidental escape of material from the container.

55 I claim as my invention:

1. A closure cap of the character described comprising a generally flat end wall with a discharge opening therein, and a generally flat cover slidably mounted on said end wall for closing said opening, said cover having an upwardly extending part constituting a handle, and said end wall being provided with guide tongues for said cover coactive with said upwardly extending part to define the limits of movement of the cover.

2. A closure cap for containers comprising, in combination, a crown, a limited discharge area in said crown, a sliding cover for closing said area, manipulating means on said cover, and means on said crown engaging said cover for guiding and retaining said cover in its sliding movements, said guiding and retaining means being engageable with said manipulating means to stop said cover in its fully open and fully closed positions.

3. A container closure having, in combination,

a limited crown discharge area adjacent to the margin thereof, an elongated slidable cover for controlling said discharge area extending entirely across the closure in the closed position, a 5 transverse finger piece at substantially the center of said cover and dividing it into forward and rear sections, a pair of tongues offset from the closure adjacent to the margin thereof remote from said discharge area and overlying the rear 10 section of said cover, and a second pair of spaced opposed tongues offset from the closure on a line intermediate the first mentioned tongues and said discharge area to overlie the forward section of the cover, said pairs of tongues coacting with 15 said sections to guide and retain the cover and being disposed to coact with said finger piece to determine the open and closed positions of the cover respectively.

4. A closure device of the character described 20 comprising, in combination, a cap having a discharge opening and two spaced pairs of offset tongues, a slidable cover having opposite sections adapted to be received and retained and guided between the respective pairs of tongues and a 25 transverse fold joining said sections and providing a handle for the cover, one side of the handle being of reduced width to permit the passage thereby of one of the pairs of tongues in the assembly of the cover with the cap.

30 5. A closure device of the character described comprising, in combination, a slidable cover member including a handle and two sections extending oppositely in slightly divergent planes, and a cap having means for receiving said sections to retain and guide said cover, the divergence of the sections effecting a frictional resistance between said means and said cap to assist in holding said cover in adjusted position.

6. The method of assembling a slidable cover 40 having oppositely extending sections joined by a transverse handle fold with a cap having spaced pairs of offset retaining and guiding tongues which includes inserting one of the cover sections endwise between one pair of tongues and receiving the other pair of tongues within the fold, and inserting the remaining section between said other pair of tongues by relatively moving said remaining section and said other pair of tongues to shift the latter out of the fold.

50 7. The method of assembling a slidable cover having oppositely extending sections joined by a transverse open mouth handle fold with a cap having spaced pairs of offset retaining and guiding tongues which includes initially positioning the cover to place one section thereof between one pair of tongues and to locate the other pair of tongues in the open mouth of the fold, and pinching the fold closed to shift the remaining cover section and said other pair of tongues relatively to move the latter out of the fold into retaining relation to the latter section.

8. The method of assembling a slidable cover 60 having oppositely extending sections joined by a transverse open mouth handle fold with a cap having spaced pairs of offset retaining and guiding tongues which includes initially positioning the cover to place one section thereof between one pair of tongues and to locate the other pair

of tongues in the open mouth of the fold, relatively shifting said cover and said cap to move said other pair of tongues from said fold and to shift the remaining cover section into place between said other pair of tongues, and pinching 5 said fold closed.

9. The method of assembling a cover having opposite coplanar elongated sections and a transverse open fold joining said sections with a cap having retaining and guiding means for said 10 cover offset from the plane of the cap, which includes inserting the cover sections under said means, and pinching said fold closed to bring said sections into diverging planes to take up clearance between said means and said cap and 15 effect frictional resistance tending to assist in holding the cover in adjusted position.

10. A closure cap of the character described comprising, in combination, a crown having a discharge opening, a liner within said cap closing said opening and having an annular weakened line registering with the outer edge of said opening to permit separation of a portion of the liner along said line to provide an opening 20 through the liner, and a sliding cover mounted 25 upon said crown for controlling said crown opening.

11. A sheet metal closure for a container comprising, in combination, a crown having a portion thereof partially severed to form a tongue 30 bendable out of the plane of the crown to provide a discharge opening, an inner liner for the closure weakened on a line coincident with the forward edge of said tongue to be separable by bending the crown tongue inwardly thereagainst, 35 and a slide mounted on the crown for closing the discharge opening.

12. In combination with a dispensing bottle 40 for viscous fluids such as honey and having a pouring neck, a closure cap for said neck, interengageable means on said neck and said cap for securing the cap on the neck, said cap having a discharge opening extending to a line adjacent the periphery of the cap and exposing a portion of the end edge of the bottle neck, spacing means between said cap and the outer end of said neck, and a cover for said opening slidably mounted on said cap for closing said discharge opening, said cover in moving to a closed position first causing an attenuation of the fluid at the exposed portion of the end edge of the bottle neck and then completely closing the opening.

13. The combination with a bottle for viscous fluids such as honey having a pouring neck, of a cap for said neck having an end wall with a discharge opening extending to a line adjacent to but inwardly spaced from the periphery of the cap and exposing a portion of the end edge of the bottle neck, means for holding said end wall spaced a short distance from said end edge, and a slidable cover for said opening adapted in its closing movement to cause an attenuation of the fluid between the cover and said exposed end edge whereby the flow of fluid is substantially stopped before the cover is completely closed.

WALTER F. STRAUB.
